UNITED STATES PATENT OFFICE.

ROBERT BAGLEY, OF LEAVENWORTH, WASHINGTON.

EMERGENCY-DERAILER.

1,180,463.

Specification of Letters Patent. Patented Apr. 25, 1916.

Application filed May 20, 1915. Serial No. 29,278.

To all whom it may concern:

Be it known that I, ROBERT BAGLEY, a citizen of the United States, residing at Leavenworth, in the county of Chelan, State 5 of Washington, have invented certain new and useful Improvements in Emergency-Derailers, of which the following is a specification.

This invention relates to devices for de-10 railing cars and has special reference to devices for carrying the de-railing frog on the engine, or tender, when it is not in use and for applying it to the rail when the train is running away.

15 The objects of the invention are to provide means whereby the engineer of a runaway train may simultaneously disconnect the engine from the train and de-rail the train, thus saving the engine from disaster 20 and making it unnecessary for the engine crew to jump from the engine.

Further objects are to provide such a mechanism as will be simple and cheap to make, easy to operate and positive in action.

25 I attain these and other objects by the devices, mechanisms and arrangements illustrated in the accompanying drawings, in which—

Figure 1 is a side elevation of a portion 30 of a geared locomotive, showing my de-railing apparatus mounted thereon, ready for use; Fig. 2 is a similar view, showing the parts in the positions occupied thereby when the de-railing frog has been thrown 35 rearward onto the rail and the first wheel of the train has begun to climb thereon; Fig. 3 is a cross-section of my apparatus on the line *a—a* in Fig. 4; Fig. 4 is a longitudinal section on the line *b—b* in Fig. 3, 40 showing the frog being placed in position on the carrier; Fig. 5 is a side elevation of the frog in position on the carrier; Fig. 6 is a plan thereof; Fig. 7 is a perspective view, from below, showing the carrier; Fig. 45 8 is a similar view of the frog; and Fig. 9 is a side elevation showing a variation of the apparatus, in which air pressure is used to project the frog instead of a spring.

Similar numerals of reference refer to 50 similar parts throughout the several views.

This invention is particularly adapted for use in logging or other freight trains and is intended to lessen the cost of a wreck due

to a train running away by reducing the damage done. When the engineer loses the 55 control of a train and it runs away, the only thing the train crew can do is to jump from the train, under considerable risk to life and limb, and the train continues its wild course until it is thrown from the track by 60 some switch, curve, or irregularity or meets some other obstruction. The damage of such a wreck is largely in the destruction of the engine. In order to reduce this cost I mount a de-railing frog on the rear of the 65 engine and, when the engineer actuates its releasing mechanism, it is projected rearward at about the same speed as the forward speed of the train, with the result that it actually will drop vertically on to the 70 track and will reach the track at practically the same instant that the wheel of the first car reaches the frog. This de-railing frog may then slide until it engages a tie and then the said wheel climbs on its back 75 and is thrown laterally by the de-railing flange thereon, thus causing the car to leave the rails. Each wheel as it reaches the said frog is thus de-railed until the resistance of the de-railed cars to forward motion has 80 absorbed the energy of the runaway train. Meantime the engine may conveniently have been detached from the train at the same time that the frog was projected from the engine.

85 Referring now to the drawings:—the engine 1 is provided with a rear sill 2 to the under side of which a pair of hangers 3 are attached. These hangers 3 extend vertically downward from the sill 2 and are 90 side by side but spaced slightly apart. A strap 4 is secured to the two hangers 3 near their lower ends, said strap extending a short distance toward the front of the engine. Two short carrier bars 5 are secured to the 95 inner sides of said hangers 3 near the lower ends, said bars 5 being substantially L-shaped and having V-shaped tracks 6 formed thereon, whereon the hereinafter described wheels of the de-railing frog are supported. 100 A pair of angle-irons 7 are also secured to the said hangers 3 above the bars 5 and parallel therewith, said angle-irons being adapted to hold the said de-railing frog down on the tracks 6. A strong spring 8 is secured 105 to the center of the strap 4 and extends

therefrom rearward and is adapted to project the said de-railing frog along the tracks, rearward, when the frog is released.

The de-railing frog 9 is constructed in substantially the same form as is usual with such a device, having a pair of legs 10, one lying on each side of the rail when in its operative position, and having claws 11 adapted to engage and hold a tie and a central car-lifting part 12 with a derailing flange 13 thereon. This device also has four grooved wheels 14 mounted on its lower flanges, said wheels being positioned so as to ride on the tracks 6 of the carrier bars 5, and a pair of flanges 15 on the upper side of each side, said flanges 15 being adapted to engage under the angle-irons 7 to hold the wheels 14 down on the tracks 6. A pair of notches 16 are formed in the lower edges 20 of two of the flanges of the frog, said notches being positioned and adapted to receive the hooked ends of the two retaining dogs 17. These dogs 17 are mounted on a rod 18 which is supported by and passes 25 through the lower ends of the hangers 3 and which is provided with a lever 19 by which the said dogs 17 are held in the notches 16 and are withdrawn therefrom to release the said frog. The lever 19 is connected by a rod 20 to the hand control lever 21 mounted on the side of the engine 1 in any convenient position. The lever 21 is provided with the usual locking means whereby it is held from accidental movement. The coupling pin 22 may be operatively connected to the lever 21 by a rod 23 or, as shown in dotted lines, may be connected to a separate operating lever 24.

As before mentioned, the spring 8 is very stiff and I have therefore devised the following means for compressing it and for bringing the frog into position in the carrier frame. The strap 4 has a central screw-threaded hole 25 therein, wherein the screw-threaded rod 26 may be screwed. This rod 26 has a crank-handle 27 formed thereon. The inner end of the rod 26 has a shank 28 adapted to pass freely through the hole 29 in the center of the frog 9. A collar 30 is connected by a pin to the end of the shank 28 and engages the inner side of the flange of the frog. Thus by turning the crank-handle 27 the rod 26 is screwed out (toward the front of the engine) and the frog 9 is drawn forward and the spring 8 is compressed. As soon as the frog has been thus drawn to its position the notches 16 are engaged by the dogs 17 and thus the frog is held from movement under the action of the spring 8, then the rod 26 may be reversed and the collar 30 removed therefrom, and then the rod may be entirely removed.

In Fig. 9 I have shown a variation in the above-described apparatus adapted for engines which have compressed air thereon for

use in air brakes or other purposes, in which air pressure is substituted for the spring 8. The cylinder 31 has a piston 32 therein and a piston rod 33 projecting rearward therefrom to engage the frog 9. The rear end of the cylinder is sufficiently open to allow the free passage of air therefrom. When air is admitted to the front end of the cylinder through the pipe 34, and when the dogs 17 have been released as above described, the piston 33 is forced rearward and the frog is projected as above described.

Having described my invention, what I claim is:

1. In an emergency de-railer, the combination with an engine traveling on a track; of a carrier frame mounted on the rear of said engine; a de-railing frog mounted in said carrier frame; and means mounted on said carrier frame and engaging said frog whereby said frog may be projected rearward to engage the rail in front of the wheel of the following car.

2. In an emergency de-railer, the combination with an engine traveling on a track; of a carrier frame mounted on the rear of said engine; guiding means mounted on said frame; a de-railing frog mounted on said guiding means; and means mounted in said carrier frame and engaging said frog whereby said frog may be projected rearward to engage the rail in front of the wheel of the following car.

3. In an emergency de-railer, the combination with an engine traveling on a track; of a carrier frame mounted on the rear of said engine; guide rails mounted on said carrier frame; a de-railing frog; wheels mounted on said de-railing frog and supported by and guided by said guide rails; and means mounted in said carrier frame and engaging said frog whereby said frog may be projected rearward to engage the track in front of the wheel of the following car.

4. In an emergency de-railer, the combination with an engine traveling on a track; of a horizontal carrier frame mounted on the rear of said engine; a de-railing frog mounted in said carrier frame; and releasable means holding said de-railing frog in said carrier frame and adapted to allow said frog to drop from the rear end of said carrier frame when said means is released.

5. In an emergency de-railer, the combination with an engine traveling on a track; of a carrier frame mounted on the rear of said engine; a de-railing frog mounted in said carrier frame; releasable means holding said de-railing frog in said carrier frame; and means mounted on said carrier frame and engaging said frog whereby said frog may be projected rearward to engage the rail in front of the wheel of the following car when said holding means is released.

6. In an emergency de-railer, the combination with an engine traveling on a track; of a carrier frame mounted on the rear of said engine; guiding means mounted on said carrier frame; a de-railing frog mounted on said guiding means; releasable means holding said de-railing frog on said guiding means; and means mounted on said carrier frame and engaging said frog whereby said frog may be projected rearward to engage 10 the rail in front of the wheel of the following car when said holding means is released.

ROBERT BAGLEY.
